STOKER

Joseph S. Bennett, Merion, Pa., assignor to American Engineering Company, Philadelphia, Pa., a corporation of Pennsylvania

Original application December 31, 1937, Serial No. 182,763. Divided and this application September 3, 1941, Serial No. 409,338

8 Claims. (Cl. 122—4)

This application is a division of my co-pending application Ser. No. 182,763, filed on December 31, 1937, now Patent No. 2,257,588, granted September 30, 1941, and the invention herein involved relates to stokers, and more particularly to stokers of the fluid cooled type.

One object of the present invention is to provide a generally improved stoker of the fluid cooled type.

Another object is to provide improved tuyère constructions for stokers of the stated character which not only effectively distribute air for combustion in the fuel bed, but which are so disposed as to be effectively cooled by fluid cooling means, thereby insuring longevity of service.

Other and further objects will become apparent as the description of the invention progresses.

Of the drawings:

Fig. 1 is a longitudinal sectional view taken through one of the retorts of a stoker of the inclined grate, multiple retort, underfeed type, showing the fluid cooling system associated therewith.

Fig. 2 is a sectional view of one of the stoker tuyère rows, taken substantially along line 2—2 of Fig. 1.

Fig. 3 is a longitudinal sectional view taken substantially along line 3—3 of Fig. 2.

Fig. 4 is a perspective view of one of the intermediate tuyère blocks, and

Fig. 5 is a perspective view of one of the clamp blocks for holding the intermediate tuyère blocks in position.

Referring to the drawings, the numeral 1 indicates a stoker of the inclined grate, multiple retort, underfeed type, consisting of alternately disposed retorts 2, and tuyère rows 3. Fuel from hoppers 4, disposed exteriorly of the front wall 5 of the furnace, is fed to the retorts by feeding rams 6, driven by any suitable power mechanism 7. Fuel is fed along each retort by a series of pushers 8 to a dead plate 9 disposed at the lower end thereof from which it is fed into an ash pocket 10 disposed at the rearmost end of the stoker. The pushers 8 are reciprocated by any suitable link and lever mechanism indicated generally at 11, and operatively connected to the power mechanism 7.

The sides of the retorts are bounded by substantially vertical walls which consist of longitudinally extending side plates 12 and 13 (Figs. 1 and 2) and a series of side tuyère members 65 and 66 are mounted at the upper ends of the said side plates 12 and 13 respectively. Extending longitudinally of each tuyère row 3 are a

pair of fluid conducting tubes 20 and 21. These tubes extend downwardly over the entire length of the stoker, and then are bent downwardly and forwardly, as shown at 22, and form a portion of the front wall of ash pocket 10. The lower ends of these tubes terminate in a header 23. The front ends of tubes 20 and 21 are bent upwardly, as shown at 24, and extend vertically in close contact with the interior of front wall 5, and terminate at their upper ends in a boiler, not shown. Also extending upwardly from header 23 and lying between each pair of tubes 20 and 21, are one or more tubes 25. These tubes extend in substantially parallel relation with the lower portions of tubes 20 and 21, and also form a portion of the front wall of ash pocket 10 until reaching the upper end thereof, when they are bent forwardly so as to extend beneath and in intimate contact with dead plates 9. The forward ends of tubes 25 then terminate in a header 26 disposed beneath the stoker. Header 23 is connected to the boiler by downtake connection 27, while header 26 is connected to the boiler by an uptake connection 28. Draft air is supplied to the furnace from a plenum chamber 29 disposed beneath the stoker, which is supplied with air under pressure by any suitable fan or blower mechanism (not shown) through a passage 30. The lower and rearwardly disposed end of the stoker receives air from a sub-plenum chamber 31, which communicates with chamber 29 through an opening 32, the size of the latter of which may be regulated by means of a damper 33.

Each tuyère member 65 comprises a vertical portion 80 terminating at its upper end in an offset arcuate portion 81, the latter of which engages the outer side of tube 20. The ends of arcuate portion 81 terminate in a pair of extended arcuate portions 82 and 83, each of which having an aperture 84 provided therein. These apertures are adapted to receive studs 85 welded or otherwise secured to tube 20 to prevent lateral movement of tuyère members 65. These studs also act as guides to insure proper contact between tube 20 and arcuate portion 81 during assembly of tuyère members 65 in position. The lower edge 86 of each tuyère member 65 is slightly inclined and engages the correspondingly inclined upper surface of a wedge member 87, the lower surface of which rests upon an inwardly extending flange 88 of the side plate 12 of the tuyère chamber. A bolt 89, secured at one end near the upper end of side plate 12, loosely receives wedge 87. The wedge 87 is actuated toward side plate 12 by a nut 91 and washer 92.

engaging the threaded inner end of bolt 90. Upon movement of wedge 87 in this manner tuyère member 65 is moved vertically into engagement with tube 20. To assemble a tuyère member 65 in position, it is first moved vertically toward tube 20 after apertures 84 have been brought into alignment with studs 85. Wedge 87 is then actuated by nut 91 to further actuate tuyère member 65 to bring the same into intimate contact with tube 20. As shown more particularly in Fig. 3, a series of passages 94 is provided at the sides of vertical portion 80 of each tuyère member 65 through which draft air may enter the fuel bed.

Each tuyère member 66 is identical in construction with tuyère member 65. Accordingly, a detailed description thereof is unnecessary. Upon reference to Fig. 2, however, it will be noted that the tuyère members 66 are secured to tube 21 by means of studs 95, and the bolt and wedge members 96 and 97, respectively.

As shown more particularly in Figs. 2 and 3, a series of intermediate tuyère blocks 140 are disposed between tubes 20 and 21. Each tuyère block 140 comprises an elongated body portion 140' which is provided with arcuate surfaces 144 and 145 at the sides thereof, which engage the inner surfaces of the tubes 20 and 21 respectively. Depending from the lower side of each tuyère block 140 is a tongue 148, the upper surface 149 of which being inclined and receives the inclined surface 150 of the tongue 151 of clamp block 143. Each clamp block 143 is provided with arcuate side surfaces 152 and 153 which in assembly engage the lower inner sides of tubes 20 and 21 respectively. Thus, to secure a block 140 in intimate contact with the tubes 20 and 21, the retaining block 143 is moved longitudinally therewith until the tongues 147 and 151 interlock. To effect a tight joint between block 140 and tubes 146 and 147, an impact may be given to the clamp block 143 to wedge block 148 tightly into engagement with the said tubes. Series of grooves 154 are provided in the arcuate surfaces 144 and 145 of each tuyère block 140. These grooves form a series of passages between blocks 140 and tubes 20 and 21, through which draft air may pass to the fuel bed.

From the foregoing description it is seen that a simplified, as well as highly efficient tuyère construction has been provided. The tuyère blocks are so constructed that a relatively large area thereof is in intimate contact with the tubes 20 and 21 and consequently they are maintained cool during all conditions of operation. This insures longevity of service. The tuyères are also so constructed that draft air is properly distributed to the overlying fuel bed.

While the embodiment herein shown and described is admirably adapted to fulfill the objects primarily stated, it is understood that it is not intended to limit the invention thereto, since it may be embodied in other forms, all coming within the scope of claims which follow.

What is claimed is:

1. A furnace tuyère structure comprising, a pair of longitudinally extending tubes disposed in spaced, substantially parallel relation, one or more tuyère blocks disposed between said tubes, said tuyère blocks comprising an elongated body portion having arcuate surfaces at the sides thereof adapted to engage the inner surfaces of said tubes, clamp blocks for said tuyère blocks, said tuyère blocks and clamp blocks having interlocking means provided thereon, so construct-

ed that when said blocks are moved relative to each other they are brought into intimate contact with said tubes and held in said position, a pair of spaced side plates, a row of side tuyère blocks disposed between one of said tubes and one of said side plates, and a second row of side tuyère blocks disposed between the other of said tubes and the other of said side plates.

2. A tuyère structure for stoker furnaces comprising a plurality of tubes disposed in spaced, substantially parallel relation, tuyère blocks disposed between said tubes, each of said tuyère blocks comprising a body portion having arcuate surfaces at the sides thereof adapted to engage the inner surfaces of said tubes, a hook depending from each of said tuyère blocks, a clamp block for each of said tuyère blocks adapted to fit against the bottoms of said tubes, hook means provided on each of said clamp blocks adapted to engage the corresponding hooks on the tuyère blocks, said hooks having inclined surfaces whereby upon movement of said hooks into interlocking position a wedging action is produced causing said tuyère blocks and clamp blocks to move into intimate contact with said tubes.

3. A furnace tuyère block comprising a substantially elongated body portion and a hook depending from said body portion adapted to engage retaining means for holding said tuyère block in position, said body portion having a substantially arcuate upper fuel supporting surface and substantially arcuate surfaces at the sides thereof adapted to engage fluid conducting tubes, and said side portions of said tuyère block having a series of grooves provided therein through which draft air may pass.

4. A furnace stoker, comprising alternately disposed retorts and tuyère rows, each of said tuyère rows consisting of a pair of spaced walls, a tuyère assembly mounted on said walls, said tuyère assembly comprising a pair of longitudinally extending tubes, a row of intermediate tuyère blocks disposed between said tubes, each of said intermediate tuyère blocks having a pair of arcuate faces adapted to engage the inner sides of said tubes, a clamp block for each of said tuyère blocks, said tuyère blocks and clamp blocks having interlocking means provided thereon so constructed that when said blocks are moved relative to each other they are brought into intimate contact with said tubes, a row of side tuyère blocks disposed between one of said tubes and one of said side walls, and a second row of side tuyère blocks disposed between the other of said tubes and the other of said side walls.

5. A furnace stoker, comprising alternately disposed retorts and tuyère rows, each of said tuyère rows consisting of a pair of spaced walls, a tuyère assembly mounted on said walls, said tuyère assembly comprising a pair of longitudinally extending tubes, a row of intermediate tuyère blocks disposed between said tubes, each of said intermediate tuyère blocks having a pair of arcuate faces adapted to engage the inner sides of said tubes, a clamp block for each of said tuyère blocks for drawing the latter into intimate contact with said tubes, each of said clamp blocks comprising a pair of arcuate faces adapted to engage said tubes, and interlocking means between said tuyère blocks and clamp blocks, whereby longitudinal movement of the latter effects movement of said tuyère blocks into intimate contact with said tubes, a row of side tuyère blocks disposed between one of said tubes and

one of said side walls, and a second row of side tuyère blocks disposed between the other of said tubes and the other of said side walls.

6. A furnace stoker, comprising alternately disposed retorts and tuyère rows, each of said tuyère rows consisting of a pair of spaced walls, a tuyère assembly mounted on said walls, said tuyère assembly comprising a pair of longitudinally extending tubes, a row of intermediate tuyère blocks disposed between said tubes, each of said intermediate tuyère blocks having a pair of arcuate faces adapted to engage the inner sides of said tubes, a clamp block for each of said tuyère blocks for drawing the latter into intimate contact with said tubes, a tongue depending from each of said tuyère blocks adapted to be engaged by a corresponding tongue on said clamp block whereby when the latter is moved toward locking position said tuyère block is drawn into intimate contact with said tubes, a row of side tuyère blocks disposed between one of said tubes and one of said side walls, and a second row of side tuyère blocks disposed between the other of said tubes and the other of said side walls.

7. A tuyère structure for stoker furnaces comprising, a plurality of tubes disposed in spaced, substantially parallel relation, tuyère blocks disposed between said tubes, each of said tuyère blocks comprising a body portion having arcuate surfaces at the sides thereof adapted to engage the inner surfaces of said tubes, and the said arcuate surfaces on said blocks having grooves provided therein providing passages for draft air when said blocks are assembled on the tubes, a

hook depending from each of said tuyère blocks, a clamp block for each of said tuyère blocks, hook means provided on each of said clamp blocks adapted to engage the corresponding hooks on said tuyère blocks, said hooks having inclined surfaces whereby upon relative movement of said tuyère blocks and clamping blocks the said blocks are urged into intimate contact with said tubes.

8. A tuyère structure for stoker furnaces comprising a pair of tubes disposed in spaced, substantially parallel relation, tuyère blocks disposed between said tubes, each of said tuyère blocks comprising a body portion having arcuate surfaces at the sides thereof adapted to engage the inner surfaces of said tubes, and the said arcuate surfaces on said blocks having grooves provided therein providing passages for draft air when said blocks are assembled on the tubes, a hook depending from each of said tuyère blocks, a clamp block for each of said tuyère blocks, hook means provided on each of said clamp blocks adapted to engage the corresponding hooks on said tuyère blocks, said hooks having inclined surfaces whereby upon relative movement of said tuyère blocks and clamping blocks the said blocks are urged into intimate contact with said tubes, a pair of spaced side plates defining a tuyère chamber beneath said tubes, one or more side tuyère blocks disposed between one of said tubes and one of said side plates, and one or more side tuyère blocks disposed between the other of said tubes and the other of said side plates.

JOSEPH S. BENNETT.
